UNITED STATES PATENT OFFICE.

WILLIAM O. GOTTWALS, OF WASHINGTON, DISTRICT OF COLUMBIA.

FILE AND INDEX.

No. 883,950.

Specification of Letters Patent.

Patented April 7, 1908.

Application filed August 7, 1903. Serial No. 168,629.

To all whom it may concern:

Be it known that I, WILLIAM O. GOTTWALS, a citizen of the United States, residing at Washington, in the District of Columbia, 5 have invented certain new and useful Improvements in Files and Indexes, of which the following is a specification.

My invention relates to that class of devices for filing letters, documents, cards and 10 other articles, in which a follower operates to release and clamp the papers, and vary the capacity of the file, by sliding along the base and by tilting into inclined and vertical positions as may be required.

15 The invention comprises two tilting file boards, of any suitable material, one or both of which may be a follower, by the operation of which, preferably in connection with suitable interposed index-leaves, pockets or folds, the papers may be openly displayed for 20 examination in what may be termed book form. Said file boards are controlled by clamping devices of any suitable character to effect said operation. I may employ clamps such as are described in my Patent No. 25 733,547 dated July 14, 1903, or clamps of the character herein described.

The improved clamp *per se* is a further part of the invention and subject of this application. Also the suspension device hereinafter described.

The invention consists in the parts and combinations thereof hereinafter set forth and claimed.

35 In order to make the invention more clearly understood I have shown in the accompanying drawings means for carrying the same into practical effect, without limiting my improvements, in their useful applications, to the particular constructions which, for the purpose of illustration, I have delineated.

In said drawings: Figure 1 is a perspective view of a file embodying my invention 45 the same showing a support or cabinet containing four of the file boxes, one of which is in its suspended and open position for the examination of its contents. Fig. 2 is a side view of one of the files. Fig. 3 is a plan view 50 of the same. Fig. 4 is a perspective view of one of the rod supports, showing also one end of the follower-supporting rod. Fig. 5 is a sectional view of a portion of the cabinet, and one of the files in place therein, showing 55 in dotted lines the suspended position of the file. Fig. 6 is a perspective view of one of

the followers with its clamp, a part of the rod being shown in dotted lines. Fig. 7 is a sectional view of the same; the follower being shown in inclined position. Fig. 8 is a perspective view of the lower end of the clamp lever.

Referring to the drawings A is a support on which the file B is suspended, and which is preferably a cabinet having one or more spaces or pigeon holes into and out of which the file may slide. When the file is thus supported its base turns up to become the front of the pigeon hole when the file is put away. I may here state that the file without a suspension device may be kept in an ordinary pigeon hole, sliding in and out on its base, or on a shelf, or may be employed as a desk file for current papers or for indexing work.

1 is the base of the file formed with a longitudinal groove 2 in which is situated a rod 3. The ends of the latter are supported in brackets 4, the bases 5 of which are driven tightly into horizontal slots 6 in the base and the vertical parts 7 of which close the ends of the groove 2 and are provided with perforations 8 for the rod. One of said perforations is slightly countersunk, as shown at 9 to accommodate the head 10 of the rod, and over said head is adapted to turn a button 11 pivoted to the bracket at 12 and arranged to maintain by gravity a position which keeps the rod in place. The opposing operation of the file board clamps is such as to put a longitudinal strain on the rod itself with little or no strain on the rod supports. The said rod, while it passes through the index cards, or tags on the index leaves or folders, so that the index devices are strung on the rod, may be removed to permit the transfer of the contents of the file as a whole, or for rearrangement or change of the index.

C are the file boards arranged to slide on the rod 3, by means of extensions or brackets 13, formed on or attached to the file board 100 and which enter the groove 2 and have perforations 14 for the rod. These perforations are elongated vertically to allow the file boards to tilt freely. Each file board has a clamping lever 15 pivoted thereto, preferably between ears 16 on the brackets 13, by a transverse pin 17. This lever has an upwardly extending handle 18 and below the pivot, an arm 19 which bears on the rod 3. At each side of the rod, the arm 19 has downward extensions 20 forming a socket 21 in which the rod is held to keep the parts in

alinement and promote the accurate and easy operation of the clamp. The parts are so arranged that when the file board is vertical (or inclined slightly inward) the socket 21 engages the rod at a point substantially vertically below the pivot 17.

When it is desired to examine the contents of the file, the two handles 18 are thrown outward by the thumbs and the file boards 10 assume the open position shown in Figs. 1 and 7, whereupon the papers or cards in the files may be turned like the leaves of a book. It will be observed that the file is very convenient of use, simple of construction, and 15 has great capacity.

At the back and front longitudinal edges of the base may be provided a back board 22 of the full height of the file, and a front board 23 which engages the lower part of the file 20 contents to keep them in place but is low in height so as not to interfere with their examination.

The cabinet A is provided with front and rear supporting rods 24, 25, at the bottom of 25 each file-receiving space. 26 26, indicate hooks attached to the back board 22 (which becomes the base when the file is in the cabinet) adapted to engage the front rod 24 as the file is drawn out, so that the file may 30 turn on said rod and be supported in vertical position for use, as seen in Fig. 1.

27 indicates recesses in the front board 23 to accommodate the hooks 26 of the file above. Other suspension means may however 35 ever be employed.

The groove 2 I intend as typical of any equivalent space or depression to accommodate the rod.

While I prefer to make both of the file 40 boards slideable longitudinally on the base, it will be understood that some of the advantages of my invention may be realized by leaving one of said boards at one place on the base and sliding the other as may be necessary.

I intend the term "file board" to include either a flat plate, open or skeleton frame, or other equivalent device adapted to support the file contents in an inclined or in a vertical 50 position.

By "base" I intend any suitable receptacle or supporting means on which the file boards may tilt and slide.

By "index devices" I include suitable index leaves, folders or pockets interposed between the two file boards. These devices may rest freely on the base, or may have perforated tabs entering the groove and strung on the rod. When folders or pockets are 60 employed to receive the filed papers in separate bodies or collections, either the contents of such folders may be readily examined while the folders are in place between the file boards, by reason of the wide opening of the 65 latter in both directions, or any folder may

be removed with its contents for examination apart from the file.

In Fig. 6 is shown a portion of an index pocket 28 having a tab 29 perforated and strung on the rod 3 between the two followers. In Fig. 1 the contents of the file, with or without index devices, are shown at 30.

I prefer to arrange a pull on the part 1 which will allow the file to rest flat on a desk, and to this end I may provide the file with an 75 undercut pull or recess 31. A label plate is shown at 32.

In order to allow the file to turn freely on the rod 24 I bevel off the front or top corners of the followers as shown at 33. The rods 80 24, 25 may be secured in place by any suitable means, such as heads, washers or "nuts 24' 25'.

As the supporting and hinge-rod 24 is situated nearly in the front vertical plane of the 85 support or cabinet A, there is possibility of the back of the receptacle B encountering the front of such support before the receptacle has reached a vertically suspended position. I therefore provide the receptacle 90 with means for projecting it a little forward relative to the support. This I effect by inclines 34 formed on the hooks 26 and which slide on the rod 24. These cause the upper part of the back 22 to clear the front of the 95 cabinet or the face of the file below.

What I claim is:—

1. In a file the combination of a base-board and two opposing tiltable file boards mounted on the base-board and within the side limits of the same, the said file boards being constructed to be outwardly inclined for the examination of papers and to be secured in vertical position for clamping the papers between them, and one of the file boards being 105 movable along the base board substantially to or beyond the middle of the same to vary the capacity of the file, substantially as set forth.

2. In a file the combination of a base-board 110 adapted to serve as either the bottom or front of the file, and two opposing tiltable file boards or followers mounted on the base-board within the side edges of the base-board, and constructed and arranged to be outwardly inclined for the examination of papers and to be secured in vertical position for clamping the papers between them, one of the said followers being movable along the base-board to a position in substantial contact with the other follower as and for the purposes described.

3. In a file the combination of a base-board and two opposing followers mounted and tiltable on the base-board, one or both of said followers being slideable along the base-board to bring the followers into substantial contact, substantially as and for the purposes described.

4. In a file the combination of a base-board 130

- having rear and front boards, and two opposing tilttable followers mounted on the base-board within the side limits of the base-board, the whole forming a box-like receptacle, the said followers being constructed and arranged to be outwardly inclined for the examination of papers and to be secured in vertical position for clamping the papers between them, one or both of the followers 5 being inwardly slideable on the base-board to bring the followers into substantial contact, substantially as and for the purposes described.
5. In a file the combination of a receptacle 15 having a base adapted to serve as the front or bottom of the file, a high wall 22 adapted to serve as the bottom or back of the file, and a low wall 23 which serves as the front of the file when the file is in position for examination, and, two opposing tilttable followers mounted on the base and arranged within the side edges of the base, one of the followers being slideable on the base to bring the followers into substantial contact when the 20 file is empty or contains few papers, substantially as and for the purposes described.
6. In a file the combination of a support, a base-board slideable and tilttable, on said support, and two opposing file boards arranged 25 within the side edges of the base-board and tilttable on the latter for the examination and for the clamping of papers, one of the file-boards being slideable along the base-board substantially or beyond the middle of the 30 same, as set forth.
7. In a file the combination of a support, a base-board which is tilttable on the same and is adapted to serve as the front or bottom of the file, said base-board being provided 35 with a back 22 which is also adapted to serve as the bottom of the file and support the contents of the latter when the file is in a closed position with the said base-board in a vertical position, and two opposing tilttable file 40 boards or followers mounted on the base-board within the side edges of the latter, one of the followers being slideable on the base-board to bring the followers into substantial contact if desired, substantially as and for 45 the purposes described.
8. In a file the combination of a base-board having a transverse groove, a back 22 attached to the base-board and arranged parallel with the groove, a rod mounted in 50 said groove, and two opposing followers tilttable on the base-board and rod and arranged to slide inward from the edge of the base-board substantially to the middle of the same, as and for the purposes described.
- 60 9. In a file the combination of a base-board formed with a groove, a follower having a perforated bracket or extension in the groove, a rod in said groove, attached to the base-board and passing through said perforation of the bracket, and a lever having a 65
- single pivotal connection with the follower and having a free unperforated end which bears directly on the upper side of the rod, substantially as and for the purposes set forth.
10. In a file the combination of a base-board, a rod attached to the same, a follower having a perforated part through which said rod passes, said part being freely tilttable and slideable on the rod, and a lever having a pivotal connection with the follower at a single fixed point and having a free unperforated end bearing directly on the rod, substantially as and for the purposes set forth.
11. In a file the combination of the 70 grooved base, a rod arranged in the groove and suitably connected at one end with the base, the base at the other end of the rod having a horizontal slot, a perforated holder for the latter end of the rod having a flange 75 driven into said slot, and paper-supporting means mounted on said rod.
12. In a file the combination with a supporting cabinet or shelf, a base-board having a suspension means on which it may tilt and 80 by which it is connected with the cabinet, and two opposing followers moving parallel with the axis of suspension and having their upper corners beveled off as shown at 85 33, substantially as set forth.
13. In a file the combination of a grooved 90 base, having horizontal slots at the ends of the groove, a rod in such groove, perforated holders for said rod having flanges driven into said slots, and paper supporting means 95 mounted on said rod.
14. In a file the combination of a grooved base, a rod in such groove, having a head at one end, perforated holders for the ends of the rod and attached to the base, and a retaining 100 means for the rod adapted to release the rod or to turn over the head of the same to retain the rod in the holders.
15. In a file the combination with a transverse rod, of a receptacle adapted to slide 110 over the rod and having hooks to engage the same whereby the receptacle may turn and be suspended on said rod and two tilttable file boards operating in the directions of the length of said rod whereby the contents of 115 the file may be inclined to the right and the left of a person examining the same while the file is so suspended, substantially as set forth.
16. In a file the combination of a receptacle, paper holding means therein, the supporting rods 24 and 25, and the hooks 26 arranged to engage the forward rod 24 when the receptacle is drawn forward, the rear rod 25 being arranged to support the rear part of the receptacle and being situated beyond the 120 range of movement of the hooks, the said hooks 26 being provided with the inclines 34 for the purpose and substantially as set forth.
17. In a file the combination of a receptacle 130

cle having two followers arranged and operating respectively at the right and at the left of the receptacle, and having the hooks 26, and the rods 24, 25 on the back of the receptacle, the forward rod 24 being adapted to be engaged by said hooks to allow the receptacle to turn in planes parallel with the followers, substantially as set forth.

18. In a file the combination of a receptacle, paper holding means therein, a support 10 on which the receptacle may turn to a sus-

pended position for examination, and hooks 26 on said receptacle adapted to engage and turn on said support and having inclines 34 to project the receptacle forward relative to 15 said support, substantially as set forth.

In testimony whereof I affix my signature in presence of two witnesses.

WILLIAM O. GOTTWALD.
